US0D1022751S

(12) **United States Design Patent** (10) Patent No.: **US D1,022,751 S**
(45) Date of Patent: ** Apr. 16, 2024

(54) **DOORBELL**

(71) Applicant: **CHENGDU QUANJING
INTELLIGENT TECHNOLOGY
CO., LTD.**, Chengdu (CN)

(72) Inventors: **Juan Li**, Sichuan (CN); **Rujia Wang**, Sichuan (CN)

(**) Term: **15 Years**

(21) Appl. No.: **35/517,002**

(22) Filed: **Mar. 23, 2023**

(80) **Hague Agreement Data**

Int. Filing Date: **Mar. 23, 2023**

Int. Reg. No.: **DM/228348**

Int. Reg. Date: **Mar. 23, 2023**

Int. Reg. Pub. Date: **Apr. 28, 2023**

(51) **LOC (14) Cl. 10-05**

(52) **U.S. Cl.**

USPC **D10/118.2**

(58) **Field of Classification Search**

USPC D10/118.2, 121

CPC G08B 3/10; G08B 13/19684; G08B 15/00; G08B 13/19695; G08B 7/06; G08B 13/19619; G08B 7/064; G08B 13/19656; G08B 19/00; G08B 25/009; G08B 13/1472; G08B 19/005; G08B 13/196; G08B 25/10; G08B 13/1966; G08B 3/1016; G08B 13/2462; G08B 13/248; G08B 13/19669; G08B 5/36; G08B 27/003; G08B 1/08; G08B 13/10; G08B 25/14; G08B 13/19613; G08B 13/19615; G08B 25/008; G08B 13/19645; G08B 21/0476; G08B 3/1041; G08B 13/19602; G08B 13/19652; G08B 13/19676; G08B 27/005; G08B 29/046; G08B 13/00; G08B 15/001; G08B 25/001; G08B 25/004; G08B 29/02; G08B 29/10; G08B 29/181; G08B 13/19608; G08B 13/19658; G08B 13/22; G08B 25/002; G08B 13/08;

CLAIM

The ornamental design for doorbell, as shown and described.

DESCRIPTION

1. Doorbell
2. Doorbell
- 1.1 : Perspective
- 1.2 : Front
- 1.3 : Back
- 1.4 : Left
- 1.5 : Right
- 1.6 : Top
- 1.7 : Bottom
- 1.8 : Perspective
- 2.1 : Perspective
- 2.2 : Front
- 2.3 : Back
- 2.4 : Left
- 2.5 : Right
- 2.6 : Top
- 2.7 : Bottom
- 2.8 : Perspective

(Continued)

The dash-dash broken lines in the drawings depict the portions of the doorbell which form no part of the claimed design.
